UNITED STATES PATENT OFFICE.

ELISHA ASBURY CONWAY, OF WILLIAMSPORT, PENNSYLVANIA.

COMBINED CHALK LINE AND PLUMB BOB.

Application filed December 30, 1924. Serial No. 758,889.

This invention relates to chalk lines and more particularly to means for removing surplus chalk from the line and yet leave sufficient thereon to insure the proper chalking by the line.

Another object is to so construct a device of this character that it may be quickly and easily changed from a chalk line to a plumb bob and vice versa.

With the foregoing and other objects in view which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings:—

Figure 1 represents a side elevation of the device shown ready for use as a plumb bob;

Fig. 2 is a longitudinal section thereof;

Fig. 3 is a longitudinal section taken in a plane at right angles to Fig. 2 showing the device ready for use as a chalk line;

Fig. 4 is an enlarged detail section showing the surplus chalk remover; and

Fig. 5 is a detail sectional view showing the connection of the top of the chalk container with the body portion thereof.

In the embodiment illustrated a cylindrical chalk container 1 is shown having a removable top 2 secured by a pin and groove connection 3 and having a central aperture for the passage of the chalk line 10. This cover 2 has depending from its inner face a surplus chalk remover 5, shown in the form of a small cylinder having a removable closure 6 at its lower end being preferably in the form of a cap threaded thereon and having a central opening 7 for the passage of the chalk line 10. This chalk remover 5 is filled with small balls or rollers, large size shot being suitable for this purpose such as is shown at 8 so that when the cord or line 10 is drawn through said balls the chalk will be wiped off leaving just a sufficient amount to make a proper mark. The container 5 is provided with a plurality of perforations 9 in one side wall thereof to permit the chalk which collects from the line to be sifted out therethrough and prevent clogging of the container. The container 5 is located above the chalk line in the container 1 so that there is no difficulty

in sifting out the chalk through the apertures therein.

A similar remover 5^a depends from the bottom of the container 1 below which is a skirt 11 in which said container 5^a is housed.

The remover 5 which depends from the top 2 of container 1 wipes off the surplus chalk from the line 10 before it is wound onto the reel 20 while the remover 5^a wipes off surplus chalk before the line is used for the purpose to which it is intended to wit making a line.

The skirt 11 is provided at its lower edge at diametrically opposite points with bayonet slots 12 designed to receive the laterally extending pins 16 carried by a plumb bob 15.

This pin and slot connection operates to hold the plumb bob 15 engaged with the skirt 11 which is connected with the casing 1. This pin and slot connection operates to hold the plumb bob 15 engaged with the skirt 11 which is connected with the casing 1. The casing 1 is designed to be used as a plumb bob suspended from the line 10, said line having a knot or other means for securing it beyond the bottom of the container 5^a.

The removable top 2 has a groove and pin connection with the container 1 to securely lock it engaged with the container to prevent the chalk therein from escaping and yet which permits the container to be filled when necessary.

The reel 20 is carried by a shaft 21 revolvably mounted in a frame 22, said shaft being provided at one end with a crank handle 23 to facilitate winding of the line on the reel.

The frame 22 is provided at its lower end with a band 24 equipped at its lower edge with a bayonet slot 25 designed to interlockingly engage with a pin 26 which projects laterally from the top 2 as is shown clearly in Fig. 1.

In the use of this device when it is desired to use it for a chalk line the plumb bob 15 is removed from the skirt 11 by disengaging the pins 16 thereof from the bayonet slots 12 and the parts will then be in the position shown in Fig. 3. The line 10 is drawn out through the chalk receptacle or container 1 and through the wiping device 5^a which leaves just sufficient chalk on the line to make the necessary mark. After it has been used the reel 20 is turned by turning the handle 23 which winds up the line 10 thereon, the chalk having been wiped therefrom in its passage through the wiper 5. The plumb bob 15 is then inserted in the skirt 11 and secured and the device then

used as a plumb bob by disengaging the reel frame 22 from the chalk container by disengaging slot 25 from pin 26 as shown in Figs. 1 and 2. The weight of the plumb bob then will drop down and cause the line to unwind from the reel 20 and it may be used in the usual manner. When finished for use as a plumb bob the line is wound up on the reel 20 and the frame with the 10 collar 24 engaged together with the top 2 of the casing and the device thus remains in compact form ready for use when desired.

I claim:—

- 15 1. In a device of the class described, a chalk container closed at both ends, a chalk line passing through said ends and through the container, an excess chalk remover mounted at one end of said container and 20 made in the form of a cylinder having balls disposed therein, said line passing through said cylinder in contact with said balls whereby the excess chalk is wiped from the line during its passage through the wiper,

25 said ball container having apertures for the discharge of chalk collected from the line.

2. A chalk container having a removable cover at one end and a depending skirt at the other, a plumb bob having a pin and slot connection with said skirt to detachably hold it engaged therewith, a reel carrying frame having a band at its lower end adapted to fit over the upper end of the chalk container, said band and container having interlocking means to detachably secure them together, and a chalk line secured at one end to said reel and passing through said chalk container and being provided beyond the bottom thereof with means to prevent the withdrawal of the line through the container in an upward direction and adapted to permit it to be drawn downwardly in the opposite direction.

30 35 40 45 In testimony that I claim the foregoing as my own, I have hereto affixed my signature.

ELISHA ASBURY CONWAY.
